UNITED STATES PATENT OFFICE.

GEORGE H. HOLLAND, OF ST. LOUIS, MISSOURI, ASSIGNOR TO THE BRIDGE & BEACH MANUFACTURING COMPANY, OF SAME PLACE.

DESIGN FOR A HEATING-STOVE.

SPECIFICATION forming part of Design No. 22,573, dated June 27, 1893.

Application filed May 26, 1893. Serial No. 475,642. Term of patent 7 years.

To all whom it may concern:

Be it known that I, GEORGE H. HOLLAND, a citizen of the United States, residing at St. Louis, State of Missouri, have invented and 5 produced a new and original Design for Stoves, of which the following is a full, clear, and exact description, reference being had to the accompanying drawing, wherein the figure represents a perspective view of a stove ornamented with my new design.

This design relates particularly to an upright, square shaped stove and consists in the shape and ornamentation of its several component parts, as will hereinafter be described.

15 The base is square shaped having its upper surface rounded and ornamented with a number of leaves, the stems of which intertwine. This base is mounted upon a similarly shaped sub-base, from the corners of which project 20 the legs, said legs being ornamented on their outwardly curved surfaces, with a leaf arranged about the center thereof. Arranged on each side of the legs of the sub-base is a large scroll having several smaller scrolls and 25 a spray leading therefrom, the two large scrolls on each side curving upwardly and across to meet each other to form a panel, in which panel are leaves having their stems crossed. Projecting laterally from the upper 30 portion of the base are foot rests in the shape of logs of wood, around which stems and leaves are helically arranged. The ash pit door has the usual draft openings, between, and on each side of which are scrolls. Raised 35

panels are arranged at the side of the ash box which panels are ornamented with leaves and their stems. A flange extends out over the ash pit door, which flange is ornamented with curved transversely arranged flutes, the upper ends of which are turned back to form 40 nubs or scrolls. Above this flange, on the front of the stove, is a door having the usual openings, and at the sides of the stove are arranged similar doors on about the plane of

the one above mentioned. Projecting downwardly and outwardly from the body of the stove from a point above these doors, is a flange ornamented on its upper curved surface with scrolls. The front of the stove above this flange, is provided with a door 45 having two rows of openings, as shown, and above this door is arranged a raised panel, ornamented with scrolls at its sides, which scrolls extend across at its upper edge to meet each other, leaving a space between for a name 50 or number. The sides of the stove above this flange are formed with a raised panel, the corners of which are ornamented with scrolls which meet each other, leaving a space in the center, in which is arranged a full blown 55 flower.

The top portion of the stove projects over the body, its lower side being curved to meet the front, sides and back of the body portion, said curved portion being ornamented with 60 scrolls. The upper portion of this top is formed rounded, and is ornamented with scrolls at its corners which form panels, in which panels are arranged leaves having their stems crossed. Arranged at the upper portion of the top is a dome-shaped cap piece 65 which is ornamented with leaves having their stems intertwined. On the top of this dome is a cylindrically shaped urn, having a top portion fluted, and a top piece in the form of 70 spraying leaves. The urn is ornamented with a spray of pointed leaves, and has arranged at its sides, dragons forming handles.

What I claim is—

The herein described design for stoves, substantially as shown.

In testimony whereof I hereunto affix my signature, in presence of two witnesses, this 17th day of May, 1893.

GEO. H. HOLLAND.
